UNITED STATES PATENT OFFICE.

DANIEL JOHN O'LEARY, OF BRUFF, IRELAND.

COMBINED RUG AND FASTENING.

1,242,717.

Specification of Letters Patent.

Patented Oct. 9, 1917.

Application filed December 14, 1916. Serial No. 136,926.

To all whom it may concern:

Be it known that I, DANIEL JOHN O'LEARY, a subject of the King of Great Britain, residing at Bruff, Limerick county, Ireland, have invented Improvements in Combined Rugs and Fastenings, of which the following is a specification.

This invention relates to improvements in combined rugs and fastenings, and has for its object to provide improved means whereby the wearer may keep dry and warm in all kinds of weather, and the said invention is designed to be worn under the usual kind of waterproof or other coat.

15 By means of my said invention the said improved fastenings may be applied in modified forms to any type of rug, old or new, and are designed to be quickly manipulated and to secure a close fit of the rug around 20 the waist and lower extremities of the person.

According to the present invention the rug is adapted to receive any form of the fastening on the waist line on the outside of 25 the rug in such a manner that when the rug is lapped approximately twice around the body of the person, one of the fastenings consisting of a strap with tapered perforations has its fixed end at or near the front 30 of the wearer or rug, said strap being extended to engage by means of any one of said tapered perforations a buckle fixed near to the opposite end of the said rug, said buckle being also on the outside of the waist 35 line of said rug.

When said strap is tightened in said buckle, this operation automatically tightens the laps of said rug around the waist of the person's body thus holding the rug in 40 position and protecting the lower extremities of the wearer, and by means of said tapered holes which are of a special shape and made large enough for easy adjustment, the buckle and strap can be rapidly engaged or disengaged in cases of emergency 45 as when driving in a vehicle, whereas this operation would be more or less delayed if the known type or the ordinary type of perforated strap was used by reason of the comparatively close fit of the buckle tongue in 50 the circular perforations in strap.

In a modified form the said strap is divided into two sections spaced and fixed at intervals to the outside of the waist line of 55 the rug, either section being adapted to engage with the said buckle. In another modi-

fied form, the said strap and buckle are made in one piece and fixed to the rug in the way described and for the purpose set forth. In a further modified form, while the said 60 buckle is fixed to the rug in the way described, the said strap is detachably connected by means of lacing or by means of string to one or other of spaced positions on the outside of the waist line of rug so as to be 65 adjustable for different sized bodies.

The said invention is more particularly described hereinafter with reference to the drawing, and the same reference numerals are used for the same parts throughout. 70

In the drawing, Figure 1 shows a general plan view of the combined rug and fastening with the rug having approximately two laps to go around the body of the person which fits into the central space, the laps being 75 shown in a loose and separated position for the sake or clearness. Fig. 2 shows a side elevation of the combined rug and fastening. Fig. 3 shows a side elevation of a modified form with two independently connected 80 straps. Fig. 4 shows a side elevation of another modification of the strap in one piece with the buckle; and Fig. 5 shows a side elevation of a further modification of the strap detachably connected to one of the 85 spaced positions on the rug.

Referring to Fig. 1 and Fig. 2, the strap 1 is sewn or riveted to the rug 2 at 3 on the outside of the waist line of the rug so that the strap portion at 3 is worn in front of 90 the person's body while the buckle such as 4 is preferably fastened to the left side and opposite end of the rug at 5 to the outside of the waist line of the rug so that it is in a convenient position for easy adjustment. 95 The strap 1 is perforated with tapered holes 6 which are spaced apart as shown and adapted to be engaged with the buckle 4 as shown in the plan view in Fig. 1, these tapered holes being made a comparatively 100 large size so that they are easily and quickly engaged with or disengaged from said buckle. In the modification shown in Fig. 3, it will be seen that the strap 1 is connected in two independent sections at 3 to 105 the rug 2, either section being adapted to engage with the said buckle, so as to provide a larger adjustment by using the strap farthest from said buckle or a smaller adjustment by using the strap nearest said 110 buckle according to the size of the person's body. In another modification shown in

Fig. 4, it will be seen that the strap 1 and the buckle 4 are in one piece and fixed to the rug at 3, so that the strap with buckle entirely surrounds the body of the wearer 5 when in use. In a further modification shown in Fig. 5, the strap 1 is perforated at 7 as is also the rug 2 at 7 in the spaced positions shown, and the said strap is detachably connected by means of lacing or 10 string 8 to one or other spaced positions as indicated at 7 on the outside of the waistline of the rug 2 so that suitable adjustments are easily made for large or small bodies by means of the tapered holes 6 and also by 15 changing the position of the strap to any one of the perforated positions shown.

In all cases the buckle 4 is positioned so as to be at or near to the left side of the person, while the straps in the various views 20 shown in Figs. 3, 4 and 5 are positioned on the rug so as to effect a suitable engagement with said buckle when the rug is lapped approximately twice around the body of a person, somewhat as indicated in Fig. 1. 25 In all cases reinforcing strips such as 9 are suitably fixed to the inside of the rug opposite the points of attachments for each of said fastenings as at 3, 5 and 7 so as to make a strong connection to the rug. The outside 30 of the rug 2 at 2 is preferably made of a waterproof material and is preferably lined inside at 10 with cloth or other suitable material; but said fastenings may be applied to any type of new or old rug in the 35 way indicated. The positions at 3, 5 and 7 correspond to the waist line of the person.

I am aware that in the prior art straps and buckles have been applied to rugs, but I am not aware of their prior application 40 to rugs in the manner, construction and combinations herein described and illustrated.

Having described my invention, I claim:

1. A combined rug and fastening com-

prising a rug adapted to lap approximately 45 twice around the wearer, a strap secured to the outside of the rug approximately at the waistline and having spaced elongated holes therein, and a buckle adapted to engage in any one of the elongated holes in the strap 50 the buckle and that portion of the strap engaged thereby being spaced from the ends of the rug so as to be available for securing the same on the body of a wearer.

2. A combined rug and fastening comprising a rug adapted to lap approximately 55 twice around the wearer, a strap fixed to the outside approximately at the waistline of the rug when the latter is in a lapped position and having a series of spaced elongated holes therein, and a buckle secured to the rug and adapted to engage in any one 60 of the holes in the strap, the said strap and buckle being spaced from the ends of the rug so as to be available for securing the 65 same on the body of a wearer.

3. A combined rug and fastening comprising a rug adapted to lap approximately 70 twice around the wearer, a strap fixed to the outside approximately at the waistline 75 of the rug when the latter is in a lapped position and having a series of spaced elongated holes therein, a buckle secured to the rug and adapted to engage in any one of the holes in the strap, and reinforcing strips 80 fixed to the inside of the rug and opposite the point of attachment thereto of the said strap and buckle, the said strap and buckle being spaced from the ends of the rug so as to be available for securing the same on the 85 body of a wearer.

Signed by me this 25th day of November, 1916.

DANIEL JOHN O'LEARY.
